UNITED STATES PATENT OFFICE

FRANK P. McNULTY, OF LOS ANGELES, CALIFORNIA

EXTENSION TABLE

Application filed March 21, 1928. Serial No. 263,231.

This invention has to do with an extension table and has particular reference to that type of table wherein the extension leaf is incorporated in the table construction and is 5 operable into and out of operating position. It is a general object of this invention to provide a simple, practical and improved table construction of the general type above mentioned.

10 It is a primary object of this invention to provide a so-called automatic extension table having a center extension leaf operable into and out of operating position without being manipulated by hand and provided with 15 dowel means whereby it is effectively braced in operating position.

Another object of this invention is to provide a table of the character mentioned having a simple, inexpensive and easily 20 operated control.

It is another object of this invention to provide a leaf-operating mechanism for a table of the character mentioned adapted to be set to positively hold the leaf in operating 25 position.

The various objects and features of my invention will be best and more fully understood from the following detailed description, throughout which reference is had to the 30 accompanying drawings, in which:

Fig. 1 is a top plan view of the table in its normal or unextended position. Fig. 2 is a top plan view of the table showing it extended or with the extension leaf in operating 35 position. Figures 3, 4 and 5 are diagrammatic views illustrating various positions of the table parts. Fig. 3 illustrating the position of the parts when the table is unactuated as shown in Fig. 1, Fig. 4 illustrating the 40 position of the parts when the extension leaf is elevated and the dowel means ready to be engaged and Fig. 5 illustrating the dowel means engaged and the extension leaf positively set in operating position. Fig. 6 is 45 an enlarged detail view of the mechanism taken substantially as indicated by line 6-6 on Fig. 1. Fig. 7 is a bottom view of the parts shown in Fig. 7, being a view taken by line 7-7 on Fig. 6. Fig. 8 is an enlarged 50 detailed view showing the lift mechanism

with the parts positioned as shown in Fig. 3. Fig. 9 is a sectional view taken as indicated by line 9-9 on Fig. 8 and Figures 10, 11 and 12 are detailed views illustrating various positions of the control and locking mechanism.

The construction provided by my invention is intended primarily for application to or embodiment in a table construction comprising two main or end sections A and B and central extension leaf L. For the purpose of facilitating a clear understanding of my invention, I have set forth a simple embodiment of the invention as applied to a table of the type just mentioned. In this table the main or end sections A and B are slidably carried by a frame 10 having sides 11. The sides 11 of the frame are mortised or notched to receive the central extension leaf L when the parts are positioned as shown in Fig. 1. The frame 10 may be supported on suitable legs 12 in a manner common to table construction and any suitable construction may be employed in slidably mounting the end sections on the frame.

The construction provided by this invention includes, generally, means 13 interconnecting the end sections A and B of the table top so that they operate together making it possible to operate the table from one end, leaf-lifting means 14 operable to raise and lower the extension leaf L and control means 15 for the operating means 14.

In the drawings I have disclosed a simple form of means 13 for interconnecting the main top sections A and B. This form of construction includes a pair of centrally pivoted levers 17 carried by a stationary central part of the frame 10 and links connecting the ends of the levers with the movable top sections A and B. The general scheme of operation of this means 13 will be readily understood from Figures 1 and 2 of the drawings.

The leaf-lifting means 14 may include one or more units or mechanisms connecting the leaf with the frame parts 11 and operable to raise and lower the leaf into and out of the plane of the end top sections A and B.

In the drawings I have shown a construc-

tion including two mechanisms, and in view of the fact that the mechanisms may be identical, I will proceed with the description of but one, it being understood that such description also applies to the other:

The leaf-lifting mechanism or means 14 may include a fixed guide plate 20 attached to a side part 11 of the frame, a bracket 21 carrying the leaf and projecting downwardly therefrom, and an operating member 22 provided with one or more cam slots 24. The guide plate 20 is a stationary vertically disposed plate having vertical guideways 25 for guiding the leaf-carrying bracket 21 vertically. The bracket 21, operating member 22 and guide plate 20 are arranged together or one next to the other, and the bracket 21 has pins 26 projecting from it through the cam slots 24 in the operating member and into the guide ways 25 in the plate 20. With this arrangement horizontal movement of the operating member 22 causes the cam slots 24 and pins 26 to cooperate so that the leaf-carrying bracket 21 is moved vertically. The operating member 22 is guided horizontally from the plate 20 by guide pins 27 which project from the plate 20 through horizontally disposed guide slots 23 in the operating member 22. The cam slots 24 are diagonally disposed. For instance, formed at an angle of about 45 degrees, and are proportioned to give the leaf-carrying bracket 21 the desired vertical movement.

The control means 15 provided by my invention provides a releasable connection between one of the end sections of the table and the operating member 22, and a releasable lock for setting the operating member 22 against movement with reference to the guide plate 20.

The control means includes, generally, a manually operable control rod 30 having a handle 31 on its outer end and a head or projection 32 on its inner end, a flange 33 projecting from the operating member 22 and adapted to cooperate with the head 32 of the operating rod, and a latch 34 carried by the flange 33 for locking the operating member with reference to the guide plate and arranged to be under control of the rod 30.

In the preferred form of the invention, the control rod is mounted on the under side of one of the end sections of the table by means of suitable mounting brackets 35 and may be a plain rod having one end turned to form the handle 31 and the other end turned to form the projection or head 32. It will be obvious that this construction permits of the parts being arranged and proportioned so that the handle 31 is conveniently located and can be easily operated. The flange 33 is preferably horizontally disposed and is formed on or attached to the operating member 22 to project horizontally therefrom.

The flange 33 has a deep notch 37 formed in

it from one end to receive the head 32 of the control rod. The head 32 of the control rod is adapted to engage the inner end 38 of the notch 37 to operate the member 22 outwardly or in a direction to cause lifting of the extension leaf, and is adapted to be operated into a recess 38^a in one side of the notch at its inner end to operate the member 22 inwardly or in a direction to lower the extension leaf. The head 32 of the control rod is adapted to be moved into and out of operating position in the recess 38^a by turning of the rod 30.

The latch 34 is pivotally carried by the flange 33 and is adapted to cooperate with a fixed projection or lug 39. The lug 39 may be on any stationary part. For instance, it may be provided on the guide plate 20 as shown in the drawings. The latch has a head 40 designed to engage and hold the lug 39 and has a notch 41 which registers with the notch 37 in the bracket when the latch is in operating position. The head 40 of the latch is designed to cooperate with the lug 39 to throw the latch to the open position shown in Fig. 3 as the mechanism is moved to the out position where the leaf is lifted. This automatic movement of the latch causes the head 32 of the operating rod to be automatically turned or moved into the recess 38^a at the inner end of the notch 37. A stop 45 may be provided on the flange 33 to stop the latch 34 in the operating positions shown in Figures 4 and 5.

In the operation of the construction the parts are normally positioned as shown in Figures 1 and 3 of the drawings. When the extension leaf L is desired for use the end sections A and B are operated or pulled outwardly causing the head 32 of the control rod 30 to enter the notch 37 in the flange 33 and the notch 41 in the latch. The head 32 cooperates with the inner end 38 of the notch 37 so that continued outward movement of the end sections causes the operating member 22, to which the flange 33 is attached, to be operated horizontally until the extension leaf is lifted to the plane of the end sections. The parts are proportioned so that the leaf does not lift until the end sections have separated enough to allow the leaf to be lifted into position between them.

When the extension leaf has been fully lifted, the handle 31 is operated causing the latch 34 to be thrown into cooperative engagement with the lug 39 so that the operating member 22 is locked against movement and the head 32 of the control rod is in position to move freely outward through the notches 37 and 41. Inward movement of the end sections A and B will then cause the dowel pins 50 or other engaging means on the adjoining edges of the end sections A and leaf L to be engaged, thus putting the table in condition for use.

To lower the leaf the end sections A and B

are moved outwardly to disengage the dowel pins 50 whereupon the handle 31 is operated to turn the head 32 so that the latch 34 is released from the lug 39 and enters the recess 38^a. The end sections A and B are then moved inwardly, causing the leaf to lower to its unactuated position as shown in Figures 1 and 3, whereupon further inward movement of the end sections will be stopped until the handle 31 is operated to disengage the head 32 from the recess 38^a. When the head is released from the recess the top sections A and B can be further moved inwardly to their original or unactuated position as shown in Fig. 1.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. A table construction including slidable end sections, a vertically movable central leaf, operating means for moving the leaf vertically, including an actuating member, and a control for the operating means including a manually operable control part and a flange on the actuating member having a notch to receive the control part for operation in one direction and having a recess to receive the control part for operation in the other direction.

2. A table construction including slidable end sections, a vertically movable central leaf, operating means for moving the leaf vertically, including an actuating member, and a control for the operating means including a manually operable control part and a flange on the actuating member having a notch to receive the control part for operation in one direction and having a recess at the inner end of the notch to receive the control part for operation in the other direction.

3. A table construction including slidable end sections, a vertically movable central leaf, operating means for moving the leaf vertically, including an actuating member, and a control for the operating means including a manually operable control part, a flange on the actuating member having a notch to receive the control part, and a locking latch operable by the control part when in the notch of the flange.

4. A table construction including slidable end sections, a vertically movable central leaf, operating means for moving the leaf vertically, including an actuating member, and a control for the operating means including a manually operable control part, a flange on the actuating member having a notch to receive the control part, and a locking latch pivotally carried by the flange and operable

by the control part when in the notch of the flange.

5. A table construction including slidable end sections, a vertically movable central leaf, operating means for moving the leaf vertically, including an actuating member, and a control for the operating means including a manually operable control part, a flange on the actuating member having a notch to receive the control part, and a locking latch pivotally carried by the flange and operable by the control part when in the notch of the flange, the latch having a notch to register with the notch in the flange.

6. A table construction including slidable end sections, a vertically movable central leaf, operating means for moving the leaf vertically, including an actuating member, and a control for the operating means including a manually operable control part, a flange on the actuating member having a notch to receive the control part for operation in one direction and having a recess to receive the control part for operation in the other direction, and a locking latch operated by the control part.

7. A table construction including slidable end sections, a vertically movable central leaf, operating means for moving the leaf vertically, including an actuating member, and a control for the operating means including a manually operable control part, a flange on the actuating member having a notch to receive the control part for operation in one direction and having a recess to receive the control part for operation in the other direction, and a locking latch carried by the flange to be operated by the control part.

8. A table construction including slidable end sections, a vertically movable central leaf, operating means for moving the leaf vertically, including an actuating member, and a control for the operating means including a manually operable control part, a flange on the actuating member having a notch to receive the control part for operation in one direction and having a recess to receive the control part for operation in the other direction, and a locking latch carried by the flange to be operated by the control part, the latch having a notch to register with the notch in the flange.

In witness that I claim the foregoing I have hereunto subscribed my name this 6th day of March, 1928.

FRANK P. McNULTY.
